REACH ASSEMBLY FOR CYCLE SADDLES

Harold E. Kalter, Elyria, Ohio, assignor to The Troxel Manufacturing Company, Elyria, Ohio, a corporation of Ohio

Application November 1, 1949, Serial No. 124,801

2 Claims. (Cl. 155—5.24)

1

My invention relates to reach assemblies for cycle saddles and relates more particularly to a reach assembly of the type employing a reach rod and a U-shaped hanger member for retaining a pair of rear compression springs. The reach assembly of my invention is preferably associated with a reach member associated with a substantially vertically disposed saddle post.

It is an object of my invention to provide improved means for rigidly mounting said reach assembly upon said saddle post.

It is a further object of my invention to provide improved means for connecting said post and reach assembly.

It is a further object of my invention to provide a new post and reach assembly construction which will be composed of few parts, which will be inexpensive to manufacture and highly efficient in use.

Other objects of my invention and the invention itself will become readily apparent by reference to the drawing forming a part of the specification, in which drawings:

Fig. 1 is a perspective view of the reach rod, saddle post, and connecting means of my invention for said post and reach rod, and showing the rear springs and hanger therefor;

Fig. 2 is an enlarged sectional view showing the assembled relationship of the post connecting means of my invention and the reach rod shown in Fig. 1;

Fig. 3 is a perspective view of a washer of the connecting means of my invention before assembly;

Fig. 4 is a perspective view of a rod mounting plate of the connecting means of my invention;

Fig. 5 is a view of the saddle post prior to assembly as hereinafter described.

Referring now more particularly to the figures of drawing, in all of which like parts are designated by like reference characters, at 2 I show a generally V-shaped reach rod having a U-shaped front portion 3 and provided with laterally extending prongs 4 and 5 at the cantle or rearward end of the rod. The prongs 4 and 5 terminate in reversely turned inwardly extending projections 6 and 7 respectively adapted to overlap laterally spaced helical compression springs 8 and 9 to secure the same thereto. The springs 8 and 9 are suspended from a U-shaped hanger 10 having a pair of vertically disposed downwardly extending legs 11 and 12 over which the springs 8 and 9 are compressed. The yoke 10, legs 11 and 12, and compression springs 8 and 9, as well as the clips 13, form no essential portion

2

of my invention and may be variously constructed. One form thereof is illustrated in the patent to Brant No. 1,670,563, dated May 22, 1928.

Essentially, my invention comprises a reach rod receiving plate 15, curved in the present invention to conform to the shape of the median and rearmost end of the transversely extending portions 16 and 17 of the rod assembly. Said transversely extending elements of the assembly are generally parallel and are each provided with a hump portion 16' and 17' at a foremost portion, a concave depression 18' and 19' centrally thereof and a hump 4' and 5' at the point of junction of the prongs 4 and 5 with the portions 16 and 17 of the integral rod assembly 2.

The plate 15 is therefore provided with a forwardly disposed hump 20 and a rearwardly arched portion 21 to accommodate the rod portions 16 and 17 seated or nested therein. The plate 15 is further provided with a pair of grooved longitudinally extending guideways 22 and 23 therein which are disposed adjacent the lateral sides of the plate 15 and the rods 17 and 16 are retained therein when the upper end 31 of a saddle post 30 is projected through the rectangular slot 24 disposed generally forwardly and centrally of the plate 15. The washer 40, having a rectangular opening 41 centrally disposed therein and corresponding in size to the opening 24 in the plate 15, is telescoped over the upper end 31 of the post 30 thereafter. A punch or other stamping tool is directed upon the upper end of the post and the washer 40 in such manner as to rivet the post end over the washer and distort the washer so that it assumes the shape shown in Fig. 2 and is tightly clamped over the rods 16 and 17, its form approximating in cross-section the pre-formed plate 15. The plate 15 is provided with a rearwardly extending lip 59 extending downwardly and outwardly forming a pair of flared ends 51 and 52 which direct the lateral ends 4 and 5 of the rod 2 towards their spring connected positions.

It will be noted that when the plate and reach rod assembly are connected as described and the punch operation completed, that the saddle post, reach assembly and connecting plate are an integral unit rigidly secured together.

Furthermore it may be noted that the plate 15 may be initially a flat or merely concave element provided with the aperture 24 and formed with the plate 40 in the shape desired by the stamping operation when the post, plate 15, plate 40 are assembled.

It will be obvious that numerous changes in

size, material and other departures of similar nature may be made from the embodiment herein illustrated and described without however, departing from the spirit of my invention or the scope of the appended claims.

I claim:

1. A reach rod and saddle post connection comprising a reach rod of the generally V-shaped type having a pair of substantially parallel longitudinally extending legs, a substantially vertically extending post having an upper portion of generally reduced cross-section affording a shoulder, a reach rod receiving plate member having an aperture therein, a second plate member having an aperture adapted to be aligned with the aperture of said first plate member, said post adapted to have its upper reduced end portion projected through said apertures, said first named plate member being disposed longitudinally under said longitudinally extending leg portions of the reach rod and provided with a rearwardly disposed portion having a pair of flared ends each of said ends adapted to seat a portion of an opposite laterally extending end of said reach rod leg elements and said second plate member being disposed over a median portion of said longitudinally extending legs of the reach rod seated in a median portion of said first plate member, the upper end of the post being riveted over said second plate member to integrally unite the post, both plate members and reach rod assembly, and said second plate member being distorted to approximate in cross-section the formation of the median portion of said first plate member.

2. A reach rod and saddle post connection comprising a reach rod of the generally V-shaped type having a pair of generally longitudinally extending legs substantially parallel throughout the length thereof, each of said legs being provided with a hump portion in its foremost portion, a

concave depression centrally thereof and a hump at its rearmost portion, said legs extending laterally of the said rearmost hump, a substantially vertically extending post, a reach rod receiving plate member having an aperture therein, said plate being provided with a forwardly disposed hump portion and a rearwardly arched portion, said plate having a pair of grooved generally longitudinally extending guideways disposed therein adjacent the lateral sides thereof, the longitudinally extending portions of said legs being seated therein, a generally rectangular washer element having an opening centrally therein corresponding to the aperture in said plate member, the post being projected through the aligned aperture in said plate member and said washer element, the upper end of the post being riveted over said washer element distorting said element to approximate in cross-section the formation of the underlying plate portion whereby guideways are formed in said washer element, said plate member being provided with a pair of flared ends and a rearwardly disposed lip portion extending downwardly and outwardly from said pair of flared ends, adapted to seat the laterally extending ends of said reach rod legs whereby the reach rod assembly is supported by said plate throughout its longitudinal and laterally extending portions.

HAROLD E. KALTER.
